(57) **CLAIM**

The ornamental design for a game housing, as shown and described.

DESCRIPTION

1. Game housing

Fig. 1.1 is a perspective view of a game housing in accordance with the present design;

Fig. 1.2 is a right side elevation view thereof;

Fig. 1.3 is a left side elevation view thereof;

Fig. 1.4 is a front elevation view thereof;

Fig. 1.5 is a back elevation view thereof;

Fig. 1.6 is top plan view thereof;

Fig. 1.7 is a bottom view thereof;

Fig. 1.8 is an underside perspective view of the game housing; and

Fig. 1.9 is an underside perspective view of the game housing wherein exemplary game piece components are depicted in unclaimed broken lines for purposes of illustration.

(Continued)

The broken lines depict unclaimed features of the game housing, depicted for illustrative purposes only.
